(57) **CLAIM**

The ornamental design for a pop-up roof for recreational vehicles, as shown and described.

DESCRIPTION

FIG. 1 is a top perspective view of a pop-up roof for recreational vehicles in an open configuration;
FIG. 2 is a right-side perspective view thereof;
FIG. 3 is right-side view thereof;
FIG. 4 is a left-side view thereof;
FIG. 5 is a front view thereof;
FIG. 6 is a rear view thereof;
FIG. 7 is a top view thereof;
FIG. 8 is a top perspective view of a pop-up roof for recreational vehicles in a closed configuration;
FIG. 9 is a right-side perspective view thereof;
FIG. 10 is right-side view thereof;
FIG. 11 is a left-side view thereof;
FIG. 12 is a front view thereof;
FIG. 13 is a rear view thereof; and,
FIG. 14 is a top view thereof.

The broken lines shown in the figures represent portions of a pop-up roof for recreational vehicles that form no part of the claimed design.
